LIQUEFIED GAS STORAGE AND DISPENSING SYSTEM

David F. Youngblood, San Antonio, Tex., assignor
to Southern Steel Company, San Antonio, Tex.,
a corporation of Texas

Application June 8, 1937, Serial No. 147,085

10 Claims. (Cl. 122—23)

This invention relates to liquefied gas storage and dispensing systems of the general type disclosed in the patent to L. J. White, No. 2,042,439 and, among other objects, aims to provide a 5 greatly improved system for storing and dispensing gas which is generated from highly volatile hydrocarbon liquid fuels, such as butane, propane, isobutane and/or mixtures of the same. The main idea is to provide novel means for 10 utilizing heat contained in flue gases and/or hot water delivered from an ordinary heating appliance, such as a standard hot water storage heater, for supplying the necessary heat of vaporization for the stored liquefied gas and/or 15 for revaporizing any condensate that may be formed in the service pipe.

Other aims and advantages of the invention will appear in the specification, when considered in connection with the accompanying drawings, 20 wherein:

Fig. 1 is a side elevation, partly in section, showing an underground system embodying the invention;

Fig. 2 is a view similar to Fig. 1 showing a 25 system above the ground;

Fig. 3 is a sectional view taken on the line 3—3 of Fig. 1;

Fig. 4 is a sectional view taken on the line 4—4 of Fig. 2;

Fig. 5 is a sectional view taken on the line 5—5 of Fig. 2; and

Fig. 6 is a fragmentary sectional view taken on the line 6—6 of Fig. 3 and shown on an enlarged scale.

In butane systems of the type disclosed in the aforesaid patent, it has been found that it is necessary to supply some artificial heat to the liquefied gas in a storage tank, even though it may be buried in the ground below the frost 40 line, especially when the demand for gas is very great or in extremely cold climates. Moreover, it is sometimes necessary to supply artificial heat to revaporize condensate formed in the gas service pipe. This invention, therefore, provides 45 novel heat exchanging means for supplying or supplementing the heat of vaporization and for revaporizing any condensate in a service pipe, utilizing the waste heat from a heating appliance, such as a hot water storage tank, installed in a 50 kitchen or basement and at a safe distance from the storage system.

Referring more particularly to the drawings, the underground system shown in Fig. 1 is somewhat similar to the general type of system disclosed in the aforesaid patent. The usual high

pressure liquefied gas storage tank 10 is buried in the ground, preferably below the frost line and the gas dispensing appliances, including the usual pressure reducing regulator, are housed within a suitable metal casing 11, extending above the 5 ground. The dispensed gas is delivered at low pressure through a low pressure gas service pipe 12, which is also buried underground and has its lowest point adjacent to one end of the tank. The buried tank is arranged in this instance to 10 absorb some of the necessary heat of vaporization from the surrounding earth fill.

In accordance with this invention, the heat absorbed from the earth fill is supplemented by waste heat contained in the products of combustion from a domestic hot water storage heater, here shown for illustrative purposes as comprising an ordinary hot water heating tank 13 which may or may not have the usual heating coil. It is shown as being heated directly by a gas 20 burner 14 arranged within an insulated casing or spaced jacket 15 supported above the level of the ground or a floor, as the case may be, and the whole heater is carried within an outer insulated housing 16 having legs 17 and a perforated, removable bottom wall 18 through which the necessary air for supporting combustion is supplied to the burner. Incidentally, the jacket or casing 15 and the tank are supported within the housing 16 by annular metal brackets 19 which also serve 25 as barriers or baffles to prevent the cold air from circulating around the outside of the jacket 15.

The burner for the storage heater is shown as being supplied with gas delivered through a pipe 20 connected to the service pipe 12. It has 35 a conventional thermostatic control 21 and the usual pilot (not shown). Cold water is supplied to the tank by a pipe 22 and hot water is delivered therefrom by a pipe 23, both pipes being shown as extending through the wall of the 40 housing 16.

The housing 16 extends above the top of the insulating jacket 15 and the warm products of combustion from the burner are delivered into the top of the housing through a flue 24 in the 45 top wall of the jacket 15.

An insulated flue or conduit 25 is shown as being connected to the top chamber of the housing 16 to conduct the warm products of combustion downwardly into the ground and it is 50 shown as being connected to one end of a closed channel 26 conveniently welded to and extending the full length of the bottom of the tank. An outlet flue or conduit 27 is connected to the opposite end of the channel and extends upwardly 55

well above the ground to provide sufficient draft, being shown as having a goose neck or return bend 28 at its upper end to prevent rain from entering it. The arrangement is such that the 5 burnt gas or products of combustion pass through the length of the channel in heat exchanging relation with the bottom of the tank 10. Even when the burner is not on the pilot will deliver some heat through the flue. In the coldest 10 weather or in very cold climates, the heat supplied in this manner is commensurate with the demand for gas because of the greater demand for hot water and the greater quantity of gas necessary to heat it.

15 Referring to Figs. 1 and 3, the gas service pipe is shown as having a condensate receiving conduit or trap 29 connected at its lowest point by a T 30. This conduit is preferably much larger than the service pipe so that it has a substantial 20 capacity and a much greater heat exchanging area. It extends downwardly adjacent to and in heat exchanging relation with the flue 25, being fastened to the flue by suitable clips 31.

In some installations, especially in cold climates, and where the demand for gas is great, 25 it is necessary to supply even more heat to vaporize the liquefied gas than is afforded by the flue gases. To that end, the hot water pipe 23 is also shown as being arranged in heat exchanging 30 relation with the tank. In Fig. 1, it is insulated above the ground and extends downwardly into the ground where it passes through the channel 26, thence, upwardly and to the house. In this example, conduits or flues 25 and 27 have 35 T's 32 carrying stuffing glands 33 for the pipe 23 where it enters and leaves the flue to make watertight connections. The arrangement is such that all hot water drawn from the storage heater gives off some heat to the gas storage tank. This 40 insures ample heat to vaporize sufficient liquefied gas for a maximum demand.

In some instances, it is desirable to install the entire system above the ground, even in cold climates. Such a system embodying this invention is shown in Figs. 2, 4 and 5. It differs from that 45 shown in Figs. 1 and 3 mainly in that the storage tank and all of the exposed pipes are suitably insulated. In this instance, the service pipe is connected to the upper end of an enlarged conduit 34 which extends into the ground well below 50 the frost line. This conduit has a T 35 above its lower end to which the lowest point of the gas main 36 is connected. That part of the conduit 34 above the ground is arranged in heat exchanging relation with the flue 25', in the same 55 manner as explained in connection with Fig. 1. Both the conduit and the flue are shown as being enclosed within the same insulating jacket. This arrangement permits the delivered gas to absorb 60 some heat from the flue as it passes downwardly to its lowest point and the heat contained in the gas will help to revaporize any condensate which drains back to the lowest point of the service main 36. However, the extension of the revaporizing 65 conduit 34 in the ground below the frost line will also serve as a revaporizing trap because it will absorb sufficient heat from the surrounding earth to revaporize the trapped condensate. This type 70 of system is much easier and more economical to install than the underground system. Moreover, all of the parts are more easily accessible for repairs and/or replacements. It is contemplated that it will be used in relatively mild climates in connection with relatively large hot

water heaters which are designed to supply a considerable quantity of hot water.

From the foregoing description, it will be seen that the improved heat exchanger and revaporizer is very efficient in operation and economical to use. It eliminates much extra cost of installing separate or independent heat exchanging devices and insures abundant heat to vaporize liquefied gas in the coldest climates and supply the maximum demand.

10 Obviously, the present invention is not restricted to the particular embodiment thereof herein shown and described. Moreover, it is not indispensable that all the features of the invention be used conjointly, since they may be employed 15 advantageously in various combinations and sub-combinations.

What is claimed is:

1. In combination with a liquefied gas storage and dispensing system of the class described 20 having an underground storage tank and a gas service pipe; a gas heating appliance; and a flue for the products of combustion from the heating appliance connected in heat exchanging relation to said storage tank and the lowest portion 25 of said gas service pipe.

2. In combination with a liquefied gas storage and dispensing system of the class described having an underground storage tank; a heating appliance having a gas burner supplied with gas 30 from said system; a gas service pipe having a revaporizer for condensate connected to its lowest portion; and a flue for the products of combustion from said gas burner connected to supply heat to said revaporizer.

3. In combination with a liquefied gas storage and dispensing system of the class described having an underground storage tank; an appliance having a gas burner supplied with gas by 40 said system; a heat exchanger associated with said tank; and a flue for the products of combustion from said gas burner extending underground connected to said heat exchanger to supply heating medium to vaporize the liquefied gas according to the gas demand.

4. In combination with a liquefied gas storage and dispensing system of the class described having an underground storage tank; a water heater having a gas burner supplied with gas from said system; a heat exchanger including a structural 50 channel having its flanges connected to the bottom of the tank; and a flue for the products of combustion from the water heater connected to said channel.

5. In combination with a liquefied gas storage and dispensing system of the class described having a storage tank; a water heater having a gas burner supplied with gas from said system; a heat exchanger associated with said tank; and a hot water service pipe connected to said water 60 heater and passing through said heat exchanger.

6. In combination with a liquefied gas storage and dispensing system of the class described having a storage tank; a water heater having a gas burner supplied with gas from said system; a heat 65 exchanger associated with said tank; a flue for the products of combustion from the water heater connected to said heat exchanger; and a hot water service pipe also connected to supply additional heat to said heat exchanger.

7. In combination with a liquefied gas storage and dispensing system of the class described having an underground storage tank; a water heater having a gas burner supplied with gas from said system; a heat exchanger associated with said

5 tank; a gas service pipe having a revaporizer for condensate connected to its lowest portion; and a flue for the products of combustion from the heater connected to supply heat to said revaporizer and said heat exchanger.

8. In combination with a liquefied gas storage and dispensing system of the class described having an underground storage tank; a water heater having a gas burner supplied with gas from said system; a heat exchanger associated with said tank; a gas service pipe having a revaporizing conduit connected to its lowest portion; and a flue for the products of combustion from the heater connected to supply heat to said revaporizing conduit and said heat exchanger.

9. In combination with a liquefied gas storage and dispensing system of the class described having a storage tank; a water heater having a gas

burner supplied with gas from said system; a heat exchanger including a structural channel connected to the tank; a flue connected to conduct the products of combustion from the water heater through said channel, then, to the atmosphere; and a hot water service pipe extending through said channel to supply additional heat.

10. In combination with a liquefied gas storage and dispensing system having an underground storage tank; a domestic water heater above the ground; a flue for the products of combustion from the water heater extending underground adjacent to the tank; a heat exchanger for the tank supplied with heat by said flue; and a hot water service pipe also connected to supply additional heat to said heat exchanger.
